CLAIM

The ornamental design for a control panel, as shown and described.

DESCRIPTION

FIG. 1 is a perspective view of a control panel showing our new design;

FIG. 2 is a top view thereof; and,
FIG. 3 is a front view thereof.

The broken lines showing in FIGS. 1-3 are for illustrative purposes only and form no part of the claimed design.

1 Claim, 3 Drawing Sheets

FIG. 1

FIG. 2

FIG. 3

UNITED STATES PATENT AND TRADEMARK OFFICE
CERTIFICATE OF CORRECTION

PATENT NO. : Des. 457,862 S
DATED : May 28, 2002
INVENTOR(S) : Falk et al.

Page 1 of 1

It is certified that error appears in the above-identified patent and that said Letters Patent is hereby corrected as shown below:

Title page.

DESCRIPTION

The following statement should be inserted before the figure description:

-- We, Kevin Lloyd Falk and Michael LaBarbera have invented a new, original, and ornamental design for a control panel as shown. --

Signed and Sealed this

First Day of April, 2003

JAMES E. ROGAN
